Primary Examiner — Dominic V Simone(74) *Attorney, Agent, or Firm* — Banner & Witcoff, Ltd.(57) **CLAIM**

The ornamental design for a shoe, as shown and described.

DESCRIPTION

FIG. 1 is a first side, rear perspective view of a shoe showing my design;

FIG. 2 is a first side view thereof;

FIG. 3 is a second side view thereof; and,

FIG. 4 is a second side, rear perspective view thereof.

The even-length broken lines are directed to environment, represent unclaimed subject matter, and form no part of the claimed design. The use of line shading and stipple shading illustrates a contrast in materials, and the line shading depicts a surface that is more transparent, more translucent, more polished, or more reflective than the surface depicted with stipple shading.
